PRESELECTING DEVICE FOR SHEET-FEEDING MECHANISMS OF STENCILING MACHINES AND THE LIKE

Aimé Armand Roy, Lyon, France

Application August 24, 1935, Serial No. 37,741
In France August 28, 1934

10 Claims. (CL 271—21)

In stenciling machines the sheets are fed in succession from a pile of sheets to the stenciling member. The sheets show a tendency to stick to each other, principally along their edges. 5 when they have been cut by a somewhat unsharp knife, and the feeding mechanism therefore sometimes feeds two sheets at the same time or, when feeding a sheet, displaces the next one from its correct position on the pile, whereby 10 it is afterwards stencilled at a wrong place along its height. The operator frequently has to raise a corner of the first sheet and to retain the second sheet of the pile during the whole stenciling operation.

15 In printing presses it has been proposed to provide sheet-buckling members acting on the top-sheet of the pile to separate it locally from the second sheet, the latter being eventually retained by pads or pressing blocks. But in the 20 devices hitherto known it has been necessary to adjust the height of the top sheet either manually or automatically during the operation. This is a considerable drawback in connection with stenciling machines.

25 According to my invention the sheet-buckling member is supported by a freely vertically movable carriage which presses said member on the pile by own weight.

The sheet-retaining member is preferably in 30 the form of a pressing block made of rubber, while the member adapted to displace the first sheet or sheet-buckling member is a roller supported by an oscillating arm and prevented from rotating by a pawl-and-ratchet mechanism 35 whereby it may return freely and without at the same time returning the displaced sheet. But both members may also be in the form of one and the same roller or group of rollers, provided the direction of the feed is parallel to the axis 40 of said roller or rollers.

In the annexed drawings:—

Fig. 1 is a side view of a device according to this invention.

Fig. 2 is a front view thereof.

Fig. 3 is a plan view thereof.

Figs. 4 to 9 are diagrams showing the operation of the device.

Fig. 10 diagrammatically shows a modified form of a device according to the invention.

50 The stenciling machine is not illustrated in the drawings since it may be of any construction. It embodies, as usual, a stenciling mechanism of any description and a sheet-feeding mechanism.

55 The sheets are fed from a sheet-supporting

plate partly shown at 1, the pile of sheets being indicated at 2. Abutments or guides 3 are arranged on plate 1, as usual, along the two lateral sides of the pile and along its outer end.

Plate 1 carries an upright 4 which forms guide 5 for a vertically sliding carriage 5. The upright 4 is preferably rectangular in cross-section, as shown, whereby carriage 5 is prevented from rotating. Carriage 5 is formed with a projection 6 which supports the pivot 7 of a double lever 8 carrying at its lower end two rubber-coated rollers 9, loose on their spindles but prevented from rotating in one direction by pawls 10 co-operating with corrugations provided along the periphery of said rollers. The latter are in contact with the pile of sheets 2.

The upper end of lever 8 is pivotally connected with a rod 11 having a reciprocating motion in synchronism with the sheet-feeding mechanism. For instance, in a stenciling machine of standard design, rod 11 may be driven by a cam keyed on the main shaft.

The carriage 5 also supports the pivot 12 of a bell-cranked lever 13 one arm of which is pivotally connected with a vertical rod 14 which 25 passes through a guide 15 fixed to carriage 5, and terminates into a rubber-coated block 16 which is pressed against the sheets of paper 2 by a spring 17.

The other arm of lever 13 is actuated by a 30 pawl 18 loose on a pin 19 forming the pivot which connects rod 11 and lever 8. At the end of the stroke of rod 11 to the right (Fig. 1) the free end of pawl 18 contacts a sloping abutment 20 fixed to carriage 5, whereby it is raised, thus 35 freeing the end of lever 13.

The carriage 5 with its related parts is supported by rollers 9 resting on the sheets 2, spring 17 being not strong enough to lift the carriage. As the thickness of the pile decreases, 40 carriage 5 gradually comes down.

The device operates as follows:

The sheet-feeding mechanism being inoperative (i. e. between two successive feeds) and rollers 9 being at the position of Fig. 1, rod 11 moves 45 to the right (direction of arrow 21, Fig. 1) thus rocking lever 8 and moving rollers 9 to the left (direction of arrow 22, Fig. 1). The latter are prevented from rotating by pawls 10, as clearly shown in the diagram of Fig. 4. On the other hand, pawl 18, pushed by rod 11, actuates lever 13 which raises block 16 against the action of spring 17. The upper sheet of the pile is therefore no longer maintained and, under the action of roller 9, it is locally displaced, i. e. its 55

edge nearest to the device is moved towards the left of Figs. 1 and 4. This motion is limited to a minor part of the upper sheet, since rollers 9 operate near an edge and not in the middle of the pile, and also because the upper sheet is retained by the action of the usual guides or abutments.

There is therefore formed a rather sharp buckle, as shown in Fig. 5 and, as it is well-known, such a kind of buckle will easily separate two sheets stuck together; thus, if the second sheet of the pile was displaced together with the upper one, it would be soon disengaged therefrom and would resume its original position owing to its elasticity.

Towards the end of the stroke of rod 11 to the right of Fig. 1, pawl 18 reaches abutment 20, as shown in Fig. 8; it is therefore raised and lever 13 is freed (Fig. 9), whereby block 16 is again pressed downwardly by spring 17. But since the upper sheet has been locally displaced, block 16 now presses against the second sheet of the pile, as shown in Fig. 6.

During the return stroke of rod 11, rollers 9 move to the right, but this time they are not prevented from rotating by pawl 10 and they roll on the sheets without displacing them (Fig. 7).

The sheet-feeding mechanism then begins its operation. It drags the upper sheet but cannot move the next one which is retained by the pressure of block 16.

At the end of the return stroke of rod 11, pawl 18 is returned in front of the upper end of arm 13 as shown in Fig. 1.

When the pre-selector is disposed along one of the longitudinal sides of the pile of sheets, block 16 may be dispensed with, the second sheet being retained by rollers 9 themselves. Considering for instance Fig. 7 and supposing that the direction of the feed is perpendicular to the plane of the drawing, it is apparent that the second sheet will be retained against being carried along together with the upper one even if block 16 were omitted since the feeding motion is parallel to the axis of rollers 9 which therefore act as fixed blocks.

The modification shown in Fig. 10 is also adapted for being placed along one of the longitudinal sides of the pile of sheets. In this case there is provided but one roller which is directly pivoted on the carriage 5 itself. Rod 11 drives a lever 23 loose on the shaft 24 of the roller 25 and the latter is formed with a lateral toothed portion actuated by a pawl 26 carried by lever 23.

Roller 25 displaces the sheets 2 in succession and, with an appropriate adjustment, there can be obtained that only the upper sheet be cleared from the roller at each stroke of rod 11, the second sheet being retained under the roller, by the pressure of the same, against being carried with the upper one since the motion of the latter is parallel to the axis of the roller.

I claim:

1. A pre-selector for the sheet-feeding mechanism of stenciling machines and the like in which sheets are fed from a pile of sheets, said pre-selector comprising in combination a vertically sliding carriage in the vicinity of the pile of sheets; a spring-pressed block carried by said carriage, said block being adapted to be vertically pressed on the pile of sheets; a substantially vertical lever pivotally supported by said carriage; a roller rotatably supported at the lower end of said lever, said roller resting on the pile

of sheets; pawl-and-ratchet means to unidirectionally prevent said roller from rotating when pushed towards the center of the pile of sheets; means to reciprocate said lever so as to locally displace the first sheet of said pile previously to the action of the sheet-feeding mechanism; means connecting said reciprocating means with said block to lift the latter from the pile when said first sheet begins being displaced, said connecting means including a disengageable pawl; and an abutment supported by said carriage to disengage said disengageable pawl substantially at the end of the active stroke of said lever so as to cause said block to press on the second sheet of said pile before said sheet feeding mechanism begins to operate.

2. A pre-selector for the sheet-feeding mechanism of stenciling machines and the like wherein sheets are fed from a pile of sheets, said pre-selector comprising a roller resting on the pile of sheets near an edge thereof, said roller having its axis parallel to the direction of the feed of said sheets; and means to rotate said roller for a limited angle previously to the action of the sheet-feeding mechanism on the first sheet of the pile so as to locally displace said first sheet and to bring said roller into contact with the second sheet to retain the latter during the next sheet-feeding operation.

3. A pre-selector for the sheet-feeding mechanism of stenciling machines and the like in which sheets are fed in succession from a pile of sheets, said pre-selector comprising in combination a vertically freely movable supporting carriage; sheet-buckling means carried by said carriage and pressed on said pile by the weight of said carriage irrespective of the height of the top sheet; and means on said carriage to actuate said sheet-buckling means.

4. A pre-selector for the sheet-feeding mechanism of stenciling machines and the like in which sheets are fed in succession from a pile of sheets, said pre-selector comprising in combination a vertically freely movable supporting carriage; a roller pivoted on said carriage and resting on said pile and pressed thereon by the weight of said carriage irrespective of the height of the top sheet, said roller having its axis parallel to the direction of feed of the sheets; and means to rotate said roller for a limited angle previously to the action of the sheet-feeding mechanism on the top sheet so as to locally displace said first sheet and to bring said roller into engagement with the second sheet to retain the same.

5. A pre-selector for the sheet-feeding mechanism of stenciling machines and the like in which sheets are fed in succession from a pile of sheets, said pre-selector comprising in combination a vertically freely movable supporting carriage; a reciprocatable sheet-buckling roller pressed on said pile by the weight of said carriage irrespective of the height of the top sheet, said roller having its axis parallel to the direction of feed of the sheets; pawl-and-ratchet mechanism to prevent said roller from rotating during its sheet-buckling stroke; and means on said carriage to reciprocate said roller.

6. A pre-selector for the sheet-feeding mechanism of stenciling machines and the like in which sheets are fed in succession from a pile of sheets, said pre-selector comprising in combination a vertically freely movable supporting carriage; a substantially vertical oscillatable lever pivotally supported by said carriage; a sheet-buckling roller pivoted at the lower end

of said lever, said roller being pressed on said pile by the weight of said carriage irrespective of the height of the top sheet; pawl-and-ratchet mechanism to prevent said roller from rotating during its sheet-buckling stroke; and means to oscillate said lever.

7. A pre-selector for the sheet-feeding mechanism of stenciling machines and the like in which sheets are fed in succession from a pile of sheets, said pre-selector comprising in combination a vertically freely movable supporting carriage; a substantially vertical oscillatable lever pivotally supported by said carriage; a sheet-buckling roller pivoted at the lower end of said lever, said roller being pressed on said pile by the weight of said carriage irrespective of the height of the top sheet; pawl-and-ratchet mechanism to prevent said roller from rotating during its sheet-buckling stroke; retaining means supported by said carriage to retain the second sheet of the pile when cleared from the top sheet; means to oscillate said lever; and means on said carriage to actuate said retaining means.

8. A pre-selector for the sheet-feeding mechanism of stenciling machines and the like in which sheets are fed in succession from a pile of sheets, said pre-selector comprising in combination a vertically freely movable supporting carriage; a substantially vertical oscillatable lever pivotally supported by said carriage; a sheet-buckling roller pivoted at the lower end of said lever, said roller being pressed on said pile by the weight of said carriage irrespective of the

height of the top sheet; pawl-and-ratchet mechanism to prevent said roller from rotating during its sheet-buckling stroke; means to oscillate said lever; a spring-pressed block carried by said carriage and adapted to be vertically pressed on said pile; means connecting said lever with said spring-pressed block so as to lift the latter from the pile during the sheet-buckling stroke of said roller, said connecting means including a disengageable pawl; and an abutment supported by 10 said carriage to disengage said pawl substantially at the end of the sheet-buckling stroke of said roller.

9. In a combination as set forth in claim 8, said connecting means comprising a pawl pivoted 15 at the upper end of said lever; a two-armed lever pivoted on said carriage, one arm of said two-armed lever having its end engaged by said pawl and the other arm of said two-armed lever being substantially horizontal; and a vertical rod 20 fixed to said block and pivoted at the end of said last-named arm.

10. A pre-selector for the sheet-feeding mechanism of stenciling machines and the like in which sheets are fed in succession from a pile of 25 sheets, said pre-selector comprising in combination a reciprocatable roller in continuous engagement with the pile of sheets irrespective of the height of the top sheet thereof; pawl-and-ratchet mechanism to prevent said roller from rotating 30 during its sheet-buckling stroke; and means to reciprocate said roller.

AIMÉ ARMAND ROY.
